UNITED STATES PATENT OFFICE.

FOKKO BRANDT, OF KANSAS CITY, MISSOURI, ASSIGNOR TO THE BRANDT & KRELL ENGINEERING COMPANY, OF KANSAS CITY, KANSAS, A CORPORATION OF KANSAS.

KNOCKDOWN PIPE DERRICK.

Application filed October 18, 1920. Serial No. 417,812.

To all whom it may concern:

Be it known that I, FOKKO BRANDT, a citizen of the United States, and resident of Kansas City, Jackson County, Missouri, have invented a certain new and useful Improvement in Knockdown Pipe Derricks, of which the following is a complete specification.

This invention relates to derricks of that class composed of metal parts detachably secured together, and is more especially designed for use in the oil fields, and my object is to produce a safe and efficient derrick of great strength and rigidity susceptible of being erected or dismantled quickly and economically.

To this end the invention consists in certain novel and useful features of construction and combinations of parts as hereinafter described and claimed; and in order that it may be fully understood, reference is to be had to the accompanying drawings, in which:—

Figure 1, is a broken side elevation of a derrick embodying the invention.

Figure 2, is a horizontal section taken on the line II—II of Figure 1.

Figure 3 is a vertical section on an enlarged scale, of one of the corner posts of the derrick; the said post being broken away as shown.

Figure 4 is an inverted plan view of one of the post caps of the derrick.

Figure 5, is a top view of the topmost coupling of one of the corner posts, and also shows a pair of braces attached thereto and broken away.

Figure 6 is a horizontal section taken on the line of VI—VI of Figure 3.

Figure 7 is a horizontal section taken on the line VII—VII of Figure 3.

Figure 8 is an elevation of a part of one of the corner posts of the derrick, showing the coupling between two members of such posts and braces extending from said coupling.

Figure 9 is a fragmentary view showing more in detail how each brace is fastened to a post.

Figure 10 is a detail perspective view of a part forming the connection between a brace and a post.

Figure 11 is a detail perspective view of an end of one of the braces.

Figure 12 is a detailed section showing the preferred arrangement of bracing connection with the couplings.

Figure 13 is a detail of the head of one of the braces as shown in Figure 12.

Figure 14 is a detailed view of a combined washer and nut used with the brace head of Figures 12 and 13.

Figure 15 is an enlarged vertical section taken on the line XV—XV of Figure 1.

Figure 16, is a section on the line XIII—XIII of Figure 15.

Figure 17 is a section on the line XVII—XVII of Figure 16.

Referring to the drawings in detail, 1 indicates a suitable foundation of concrete or the like, and 2 a platform or base mounted upon the foundation, these parts being of any conventional or preferred type. Arranged upon the foundation at equal distances apart and radially with respect to a common center, are four corner brackets 3, each provided with reinforcements 4 for bolt holes through which bolts 5 are secured to anchor the corner brackets to the foundation, and each corner bracket is provided with a reinforcement 6 providing a cylindrical pivot socket 7, extending at right angles to said common center. Each corner bracket is also provided with a rib 8 extending radially inward from the socket and provided with an upstanding arm or stop 9. At opposite sides of the stop, each bracket is also provided with a pair of ribs 10 terminating in cylindrical lugs 11, for a purpose which hereinafter appears. A cylindrical cup 12 for each corner bracket, is provided with a depending pivot 13 engaging the socket 7 of the corresponding bracket, the arrangement being such that the pivotal engagement between the cup and bracket must be effected by endwise movement of the pivot, and to prevent such movement after the connection has been established, the cup is provided with a pair of inwardly-projecting lugs 14 to engage opposite sides of the arm or stop 9, inward swinging movement of the post being prevented by an adjusting screw 15 extending through the cup and engaging the outer side of the arm or stop. Each corner post of the derrick, consists of a series of aligned tubular pipes or sections 16, the undermost one fitting in the cup 12 and being secured

therein by the adjusting screw 15. Tubular couplings 17 connect the upper ends of the pipes or sections 16 with the lower ends of the adjacent pipes or sections 16 and have 5 internal ribs 18 resting upon the lower pipes or sections and forming supports for the overlying pipes or sections, the chambers 19 receiving the upper ends of the pipes or sections, and the chambers 20 receiving the 10 lower ends of such pipes or sections. The upper end of each coupling is provided with a flaring mouth 21, to facilitate the fitting downwardly therein of the adjacent pipe or section and the couplings are slit as at 15 22 and formed with lugs 23 engaged by clamping bolts 24 and securing nuts 25, as shown by Figures 3 and 6, to secure said pipes or sections firmly in place, and to prevent turning movement of the pipes or sections they are provided with cross pins 25^a, 20 projecting into the slits of the couplings. As a precautionary measure, fastening pins 26 are extended through said couplings and the upper end of the pipes or sections 25 16, and each of the couplings connecting adjacent pipes or sections is provided at its lower end with an inwardly-projecting perforated lug 27 and a similar outwardly projecting lug 28. Mounted upon the topmost 30 pipes or sections are inverted sockets 29 corresponding in a measure to sockets 12 and to the couplings 17. Like the latter, they are provided with internal ribs 30 to rest upon the topmost pipes or sections and with chambers 31 to receive the same, and with cross pins 32 to make the connection secure. They are also provided at their lower ends with inwardly-projecting perforated lugs 33, corresponding to lugs 27 and outwardly-projecting 35 40 perforated lugs 34, corresponding to lugs 28. Like the caps 12, they are provided with cylindrical pivot heads 35, engaging corresponding sockets 36 formed in cap plates 37, and adjusting screws 38 extending through perforated lugs 39 of said sockets 29, engage the cap plates 37 between parallel lugs 40 thereof, these screws 38 limiting pivotal adjustment of the cap plates with respect to the sockets 29, so that regardless of the inclination of the posts, the cap plates can be secured in horizontal position. The cap plates are provided with perforations 41 through which they are bolted to a skeleton top frame, preferably composed of 55 I-beams 42 and 43. A skeleton construction of pipes and couplings as described, will be rigid and strong and cannot possibly collapse, but to stiffen it to carry heavy loads such as is imposed upon derricks in oil pumping operations, the corner posts must be braced, and this is accomplished in the present construction by horizontal braces 44 and crossed inclined braces 45. For purposes of economy in and rapidity of erection and dismantling of the derrick, and for

producing a strong and rigid derrick, the construction and arrangement of the bracing is as follows:

The braces are preferably pipe sections engaging stud-bolts 46 of the respective couplings, the braces 44 connecting couplings in the same horizontal plane, and braces 45 connecting the lower ends of a pair of couplings to the upper ends of an adjacent pair of couplings, as shown most clearly by Figure 75 1. Each pipe section is provided with a flattened head 47 at each end, so that said flattened heads may fit flatly and squarely against flattened ribs 47^a formed on the couplings, the faces of said ribs standing at right angles to each other so that the braces of adjacent sides of the derrick shall occupy a corresponding relation when viewed in plan. The heads 47 are provided with notches 48 to hook over the bolts 46, and at their outer side, the heads are provided at opposite ends of the notches 48, with lugs 49, and at the upper end of the notches with outwardly-projecting stiffening ribs 50 of semi-circular form. Flat washers 51 are provided with circular perforations 52 fitting over said ribs and the bolts 46. By this arrangement, it is impossible for the hook ends of the braces to become disengaged from the bolts unless the washers are first displaced, and the bolts are reinforced by said ribs in the sense that the strains and stresses imposed on the bolts are more widely distributed thereon. The washers are prevented from turning on the bolts by the provision of recesses 53 receiving the lugs 49, and the retaining nuts 54 engaging the ends of the bolts bear against said washers and the ribs 50. In Figures 12, 13 and 14, a slightly different type of construction for fastening the ends of the braces to the corner posts is shown, this construction showing the nuts and washers integral to provide one less part to handle in securing each end of a brace to or disconnecting it from a corner post. In accomplishing this result, the washer is of ring form as at 54^b so as to not only fit over the rib 50^a but entirely overlie the ribs 49^a so as to be capable of turning with the nut 54^a, the hole 54^c of the ring washer like the hole of the washer, 52, receiving the rib 50^a. It will thus be seen that the principle and result is the same, but that where the nut and washer are combined or in one piece, the washer must turn instead of slide on the bolt. 115 120

To still further increase the stiffness and strength of the derrick, the braces 45 are clamped firmly together at their crossing points by clamps which are adjustable to accommodate the angle of the braces. Each of said clamping devices is constructed as follows:

A plate 55 is fitted against one of the braces, and a staple or U-bolt 56 slidably 130

through said plate, one leg of the staple being riveted at its end and the other threaded as at 57 and engaged by a nut 58 and washer 59, proper adjustment of said nut 56 effecting sliding action of the staple through the plate. A sleeve 60 is mounted on the staple and terminates in a pivot or swivel head 61. A pair of oppositely-bowed jaws 62 are formed with recesses 63 10 jointly forming a circular opening, and with inwardly-projecting flanges 64, the recesses receiving the enlarged portion of the pivot or swivel head 61, and the flanges fitting the neck of said head. By this arrangement, 15 the jaws can be turned to accommodate the angle of the braces to which they are applied, as shown in Figure 15. The proper adjustment of the nuts 58 will then draw the staple through the plate and thus cause 20 the crossed braces enclosed within the staple, to be clamped firmly and tightly together. Derricks for use in oil fields, must accommodate certain machinery, such as the bull wheel and the calf wheel, at opposite sides, 25 and to provide the space for the accommodation of the bull wheel and its accessories, the crossed braces are dispensed with between the platform and the first set of braces 44. By preference, posts 66 are made of 30 sections mounted at their lower ends in sockets 67 secured upon the platform, and the two sections, are connected by couplings 69, connected by inclined braces 70 to the corner posts 16, the space between posts 66 35 being for the reception of the bull wheel and appurtenances thereof. The same construction is provided at the opposite side for the calf wheel, and simply to differentiate on the drawing, posts 71 corresponding to posts 40 66 are shown, the posts 71 like posts 66, being likewise braced by inclined braces. As these form no particular part of the invention, the construction is not detailed. As it 45 is essential to ascend the derrick at times, one of the corner posts is shown as equipped with steps 72, these steps not being detailed as they form the subject matter of a separate application.

At the top of the derrick, equipment is 50 provided for establishing an operative connection between the power mechanism not shown at the bottom of the derrick, and the drilling mechanism, the equipment shown being constructed as follows:

55 73 indicates a trussed crane provided about midway its length with a forked bracket 74 fitting over one of the perforated lugs 33 and pivoted thereto, the lower end of the crane which is preferably inclined as shown, being secured to one of the corresponding lugs 27, as shown in Figure 1. Suspended from the upper end of the crane, is a block and tackle mechanism, comprising a sheave 75 and a cable 76, the latter 60 being extended down through the derrick

and attached at one end to the power mechanism mentioned and at its other end, to the drill or the like, such as a pumping rod, not shown.

It will be noted that all of the couplings 17 have the perforated lugs 27 and 28 and are therefore interchangeable as regards coupling the corner post sections and forming a support for the crane. The outwardly-projecting lugs 28 subserve a similar function in conjunction with a lug 34 of a top socket 29, as at times it may be desirable to set the crane at the outer side of the derrick to lift supplies, especially where the derrick is used as a scaffold. In such case, the corner posts will preferably be vertical. The outer lugs 28 and 34 also constitute convenient points for the attachment of guy ropes (not shown) where the greatest possible strength is necessary.

From the above description, it will be apparent that a derrick of this character will possess great strength and rigidity and that it can be erected economically by two men without the use of ladders other than the application of additional steps 72 as the erection proceeds. The only heavy portion of the derrick is the top frame, and that can be raised to position by the block and tackle mechanism of the derrick after the latter is erected to its full height, the same mechanism being employed to lower said frame should it be desired to dismantle the derrick. It will be noted that if the pipe sections 16 are of uniform length, the crossed braces 45 at different elevations, will extend at different angles as shown by Figure 1, due to the upwardly tapering form of the derrick, and for this reason the swiveled relation between the sleeves 60 and the pipe-clamping jaws 62 is essential. As the construction of the various parts has been described in detail, it is not deemed necessary to recapitulate further, it being obvious that various changes may be resorted to without departing from the principle of construction involved.

I claim:

1. A derrick comprising corner posts pivotally supported at their lower ends, and leaning inwardly toward a common center, means carried by the posts adjacent their lower ends for limiting such leaning movement, a frame connecting the upper ends of the posts, and means for bracing the posts.

2. A derrick comprising corner posts leaning inward toward a common center, means for limiting such leaning movements, caps pivotally mounted on said posts respectively, and a frame connecting the caps.

3. A derrick comprising corner posts leaning inward toward a common center, means for limiting such leaning movements, caps pivotally mounted on said posts respectively,

- a frame connecting these caps and means for securing the caps in horizontal position.
4. A derrick comprising corner posts leaning inward toward a common center, means for limiting such leaning movements, caps pivotally mounted on said posts respectively, and thrust screws engaging the posts and caps to hold the latter in horizontal position.
- 10 5. A derrick comprising a suitable support provided with pivot sockets and lugs inward of such sockets, posts pivotally engaging said sockets and leaning toward a common center, thrust screws engaging said posts and lugs to limit the leaning movement of the posts, and a frame connecting the upper ends of the posts.
- 20 6. A derrick comprising a suitable support provided with pivot sockets and lugs inward of such sockets, posts pivotally engaging said sockets and leaning toward a common center, thrust screws engaging said posts and lugs to limit the leaning movement of the posts, means to prevent movement of the posts laterally of planes radiating from such common center through the posts, and a frame connecting the upper ends of the posts.
- 30 7. A derrick comprising spaced plates provided with cylindrical sockets extending at right angles to a center common to and equal distances from said sockets, posts having cylindrical pivot heads engaging said sockets respectively, and leaning inward, means for limiting the leaning movement of the posts, means for preventing endwise movement of said pivot heads in said pivot sockets, and a frame connecting the upper ends of said posts.
- 40 8. A derrick comprising spaced plates provided with cylindrical sockets extending at right angles to a center common to and equal distances from said sockets, posts having cylindrical pivot heads engaging said sockets respectively, and leaning inward, means for limiting the leaning movement of the posts, means for preventing endwise movement of said pivot heads in said pivot sockets, cylindrical pivot heads at the upper ends of the posts, paralleling the first named pivot heads, caps having cylindrical sockets engaging said heads, means for holding the pivoted caps horizontal and against slidable movement on the top pivot heads of the posts, and a top frame secured to said caps.
- 50 9. A derrick comprising a support, four corner plates thereon, corner posts pivotally secured at their lower ends on said plates and each composed of a plurality of members and couplings connecting said members, caps pivotally mounted on said posts respectively, a frame connecting said caps, and crossed braces connecting the posts.
- 60 10. In a derrick, a corner post comprising alined pipe sections, a coupling receiving and resting on the upper end of one of the sections and receiving the lower end of and supporting the next section above; the part of the coupling receiving the upper section, being slit, means to clamp the coupling on said last named section, and a pin projecting from the latter into said slit.
- 70 11. In a derrick, a base plate provided with a horizontal pivot socket, and an upstanding lug, a cup pivotally connected to said socket and provided with a pair of lugs engaging opposite sides of the first-named lug, and a thrust screw extending through said cup and engaging the adjacent face of upstanding lug.
- 75 12. In a derrick, a post, an inverted cup upon the post, provided with a pivot-head, a cap pivotally engaging said head and overlying the cup, and means for limiting pivotal movement of the cap in one direction and preventing relative rotation horizontally of the cup and cap.
- 80 13. In a derrick, a corner post comprising alined pipe sections, a coupling carried by the upper end of one of said sections and receiving the lower end of the next section above; the part of the coupling receiving the upper section being slit, and a pin bearing a fixed relation as regards said last-named section and projecting into said slit.
- 85 14. In a derrick, a corner post comprising alined pipe sections, a coupling carried by the upper end of the lower section and receiving the lower end of the next section above and having an internal rib for abutment by the end of said upper section; the part of the coupling receiving the upper section being slit, and a pin bearing a fixed relation as regards said last-named section and projecting into said slit.
- 90 15. In a derrick, a corner post comprising alined pipe sections, a coupling carried by the upper end of one of said sections, a coupling carried by the upper end of one of said sections and receiving the lower end of the next section, said coupling having an internal rib resting on the upper end of the lower section and abutted on its opposite side by the lower end of the upper section; the part of the coupling receiving the upper section being slit, and a pin bearing a fixed relation as regards said last-named section and projecting into said slit.
- 95 In testimony whereof, I hereunto attach my signature.
- 100 FOKKO BRANDT.
